UNITED STATES PATENT OFFICE.

WILLIAM H. DANIEL, OF BIRMINGHAM, ALABAMA.

WATER CUT-OFF.

1,067,409.

Specification of Letters Patent.

Patented July 15, 1913.

Application filed May 7, 1912. Serial No. 895,702.

To all whom it may concern:

Be it known that I, WILLIAM H. DANIEL, citizen of the United States, residing at Birmingham, in the county of Jefferson and 5 State of Alabama, have invented certain new and useful Improvements in Water Cut-Offs, of which the following is a specification.

This invention relates to cut-off devices for automatically cutting off the flow of 10 water when the temperature decreases to the freezing point and thus preventing the freezing of water in the supply pipes, and has for one of its objects to provide a device of this character of improved construction 15 and increased efficiency and utility.

Another object of the invention is to provide a simply constructed device which may be applied without material structural changes to water systems of various kinds, 20 and which will not interfere with the flow of the water under normal conditions, but which will automatically cut off the water, and likewise provide for the drainage of the water which remains in the supply pipes in 25 event of the temperature falling below the freezing point.

With these and other objects in view, the invention consists in certain novel features of construction as hereafter shown and 30 described, and then specifically pointed out in the claims.

The improved apparatus may be applied to water conductors of various forms and sizes, but is designed more particularly for 35 use in connection with the ordinary water supply of residences, but it will be understood that the improved apparatus may be employed without material structural change to water supply pipes of any character, and it is not desired therefore to limit 40 the invention in any manner in this respect.

For the purpose of illustration the improved device is shown applied to an ordinary water supply for a residence, and includes a conventional sink spigot.

In the drawings employed for illustrating the preferable embodiment of the invention: Figure 1 is a sectional elevation of the improved device in operative position with the 50 parts arranged to permit water to flow therethrough; Fig. 2 is an enlarged sectional detail of the cut-off valve; Fig. 3 is a plan view of valve as shown in Fig. 2.

Corresponding and like parts are referred 55 to in the following description and indicated

in all the views of the drawings by the same reference characters.

The water supply pipe is represented at 10, and a conventional sink spigot at 11. Connected between the pipe 10 and the spigot 11, is a valve casing preferably similar to a "globe" valve and represented as a whole at 12, and provided with an internal valve seat 13 having a downwardly opening valve 14 operating in connection therewith. 60 Depending from the casing 12, is an internally threaded boss 15 having a threaded plug 16 engaging therein and formed hollow to receive a spring 17 which bears against the valve 14 and normally retains 70 the same in closed position when the pressure for opening it is removed therefrom. Rising from the casing 12, is an externally threaded sleeve 18 through which a rod 19 operates and engages the wing portion 20 of the valve 14. The rod 19 is provided with a longitudinal bore 21 having a lateral vent 22 communicating therewith, while the wing portion 20 of the valve is provided with a longitudinal bore 23 in constant vertical 80 alignment with the bore 21 and provided with a lateral branch 24 leading through one of the wings 20, and opening into the discharge side of the valve casing 12.

It will be noted by reference to Fig. 1, 85 that when the rod 19 is in its downward position, the lateral branch 22 will be closed by the packing cap 26 of the casing 12, the object to be hereafter explained.

The casing 12 is likewise provided with 90 bosses 23 in which spaced rods 24 are threaded, and thus stand vertically and in parallel relations to the rod 19. At their upper portions the rods 24 are threaded and provided with an adjustable transverse head member 25 held in position thereon by clamp nuts 26, while an intermediate transverse member 27 engages the threaded portions of the rods and is held in position by clamp nuts 28. The two members 25-27 95 are thus spaced apart a considerable distance. At its upper end the rod 19 is provided with a transverse head 29 having a disk 30 of soft metal such as copper in its upper face. The member 25 is provided with a threaded aperture through which a screw or clamping member 31 operates and provided with a wing nut 32 to enable it to be readily rotated. At its lower end the screw 31 is provided with a swiveled foot 100

110

member 33 having a soft metal bearing disk 34 such as copper, embedded in its lower face and confronting the soft metal disk 30. Extending between the two disks 30-34 is a tubular member 35 of glass or like fragile material and designed to contain water or other liquid which will readily freeze when the temperature falls below the freezing point and be thereby fractured and release the rod 19 and permit the spring 17 to automatically close the valve 14 and shut off the further flow of water. The movement of the spring and valve 14 will elevate the rod 19 and expose the vent 22 above the packing cap 36 of the projection 18 and thus prevent the creation of a vacuum and permit the surplus water to drain off through the vent passage formed by the bores 44-43-21 and 22. By this simple means it will be obvious that so long as the water remains at a temperature above freezing, the "cartridge" 35 will remain intact and hold the valve 14 in open position and permit the water to flow, but in event of the falling of the temperature below the freezing point, the cartridge by freezing, and bursting, will release the valve and permit the spring to close it.

The faucet 11 is provided with a depending hollow boss 37 and provided with an upwardly opening valve seat 38 to receive a small valve 39 which is held water-tight by the pressure of the water in the faucet below the valve 45 of the same. The valve 39 is relatively light and is held closed by the ordinary water pressure but when the "cartridge" 35 is fractured by the frost and the flow of water automatically cut off by the action of the valve 14, the pressure of water upon the valve 39 will also be reduced so that the outside air pressure will elevate the valve 39 and thus provide a vent to permit the water between the valve 45 of the faucet and the valve 14 to drain off through the vent passage and be thus prevented from freezing in the pipes and faucet section of pipe. The valve 39 is thus inoperative so long as the apparatus is operating under normal conditions, but will be automatically released and become effective to assist in draining the faucet pipe leading thereto when the water supply is cut off, as above noted.

All of the parts will preferably be of brass or like non-corrosive metal, and may be of any required size or capacity to adapt it to water conductors of various sizes and under various pressures.

Having thus described the invention, what is claimed as new is:

1. An automatic cut off comprising a casting adapted to be connected into a conduit and provided with an upwardly directed sleeve and an internal diaphragm having a valve seat, a valve adapted to engage said

seat and provided with a web having a laterally and upwardly directed vent adapted to open into the discharge side of the diaphragm when the valve is closed, a spring operating to close said valve, a movable rod passing through said sleeve and engaging said web and provided with a vent registering with the vent of the web and having a lateral outlet which is withdrawn within the sleeve when the rod is disposed in its lower position, and an element capable of being fractured by change of temperature and engaging said rod so as to hold the valve open against the resistance of the spring. 70 75

2. An automatic cut-off comprising a casting adapted to be connected into a conduit and provided with an internal valve seat, a valve for engaging said seat, a spring tending to close said valve, a rod engaging said valve, a pin adjustable toward and away from said rod, and a container for an element capable of fracturing the same upon abnormal change of temperature interposed between said pin and rod so as to hold the valve open against the resistance of the 80 85 90 spring while said container is intact.

3. An automatic cut-off comprising a casting adapted to be connected into a conduit and provided with an internal valve seat, a valve for engaging said seat, a spring tending to close the valve, a rod engaging said valve, a stationary head member, a pin adjustably engaging in said head member, and an element capable of being fractured by change of temperature interposed between 95 100 105 said pin and rod so as to hold the valve open against the resistance of the spring while said element is intact.

4. An automatic cut-off comprising a casting adapted to be connected into a conduit and provided with an internal valve seat, a valve for engaging said seat, a spring tending to close the valve, a rod engaging said valve and provided with a bearing head, a stationary head, a pin adjustable in said stationary head and carrying a swiveled bearing foot, and a tubular member of fragile material engaging between said bearing head and bearing foot so as to hold the valve open, said tubular member containing 110 115 an element capable of fracturing the tubular member when subjected to abnormal change of temperature.

5. An automatic cut off comprising a casting adapted to be connected into a conduit and provided with an internal valve seat, a valve for engaging said seat, a spring tending to close said valve, a rod engaging said valve and extending in alinement with the longitudinal axis thereof, a clamping member adjustable toward and away from said rod and operating in longitudinal alinement therewith, and a container for an element capable of fracturing the same upon abnormal change of temperature interposed be- 120 125 130

tween said clamping member and rod so as to hold said valve normally open.

6. An automatic cut off comprising a casting adapted to be connected into a conduit and provided with an internal valve seat, a valve for engaging said seat, a spring tending to close said valve, a rod engaging said valve, a head member, means for adjusting said head member toward and away from said valve, a clamping member adjustably engaging said head member, and an element capable of being fractured upon abnormal change of temperature interposed between said clamping member and rod so as to hold the valve open against the resistance of the spring while said element is intact.
7. An automatic cut off comprising a casting adapted to be connected to a conduit and provided with an internal valve seat, a valve for engaging said seat, a spring tending to close the valve, a rod engaging said valve

and provided with a bearing head, another head spaced from said bearing head, means for adjusting said last mentioned head toward and away from the bearing head, a member adjustably disposed in the adjustable head and carrying a swiveled bearing foot, and a tubular member of fracturable material engaging between said bearing head and bearing foot so as to normally hold the valve open against the resistance of the spring, said tubular member containing an element capable of fracturing the tubular member when subjected to abnormal change of temperature. 35

In testimony whereof I affix my signature in presence of two witnesses.
